UNITED STATES PATENT OFFICE.

CHARLES FRANCIS JENKINS, OF WASHINGTON, DISTRICT OF COLUMBIA.

FLYING-MACHINE.

1,081,504.

Specification of Letters Patent. Patented Dec. 16, 1913.

Application filed July 18, 1910. Serial No. 572,589.

To all whom it may concern:

Be it known that I, CHARLES FRANCIS JENKINS, citizen of the United States, residing at Washington, District of Columbia, 5 have invented certain new and useful Improvements in Flying-Machines, of which the following is a specification.

This invention relates to flying machines, and has for its main object the maintaining 10 of automatic equilibrium. This is accomplished by supporting the driving motor in such manner that it will act as a gyroscope, and, employing rotary motion derived from the motor, automatically manipulate the 15 stabilizing devices. It is not important whether these stabilizing devices be warping wing edges, auxiliary planes, or other means.

The drawings accompanying this specification 20 are largely diagrammatic, as this is believed to be sufficient for a clear understanding of the principles involved as well as their application.

In the drawings, Figure 1 is an elevation 25 of an aeroplane showing a possible location of the motor; and Fig. 2 is a larger bottom view of the floating ring which carries the friction wheels employed in winding and unwinding the cords fastened to the 30 stabilizing devices.

In both figures like symbols refer to like parts in which,

1 is a rotary-cylinder motor for driving, through suitable means, the propeller 2 of an 35 aeroplane. The upper end of the crank-shaft of the motor is fixedly held in a pivotally supported frame, as in a "universal" or gimbal suspension. Upon the other extremity of the motor sleeve 4 the friction 40 wheel 5 is fastened, and this is free to rotate inside of and normally just clearing the friction wheels 6 and 6' and 7 and 7'. The former are both fixed on shaft 8 and the latter on shaft 9. Shaft 8 has the drum 11 also 45 mounted thereon, while the drum 10 is mounted on shaft 9. These two shafts are journaled in the floating ring 12, which latter is movably mounted in the frame of the aeroplane, and held by rack arms 13 and 17. 50 This floating ring is given a fore and aft movement by means of the rack 13 and worm 14, which latter is fastened on shaft 15 on the other end of which the hand wheel 16 is mounted. Lateral movement is given 55 the ring by means of the lever 17, pivoted at 18, the opposite end of the lever having

a rack 19 engaging with a worm 20, fastened to the shaft 21 on the other end of which the hand wheel 22 is secured. Loosely mounted on the shaft 21 is a hand wheel 23 having a winding drum 24 secured thereto. On the shaft 15 is similarly mounted a hand wheel 25 having a winding drum 26. The member 30 of the cord 30^a extends outward and attaches to the stabilizing plane at the 65 right (not shown) while the member 30' attaches to a similar plane at the left. The cords 31 and 31' also attaches to the same planes, right and left, respectively. The cord 32 and 32' attaches to the elevating 70 planes to raise and lower it, while the cord 33 and 33' is also similarly attached.

The operation of the device is as follows: With the motor in rotation, and assuming the aeroplane in free flight, the tipping of 75 the aeroplane, for example, the depression of the left plane, will bring the face of the wheel 5 on the motor into frictional contact with the wheel 7 which will rotate the drum 10 winding in the cord attached to the left 80 stabilizing plane causing the machine to instantly right itself. Obviously, the tipping of the machine to the right will cause reverse rotation of the drum 10 and therefore pull down the plane on that side again righting the machine. So, likewise, the tipping 85 of the machine downward or upward would cause rotation of the drum 11 the one way or the other to right it. Turning the wheel 16 to pull the floating ring 12 toward the 90 front would act the same as though the machine should incline more or less downward, that is, it would cause the machine to rise, which it would continue to do until the wheel was turned again into middle position. 95 It is also obvious that similarly the right or left plane of the machine might be raised in the same manner, by the manipulation of the wheel 22. Should the motor stop, by design or accident, the steering would then be accomplished by the wheels 23 and 25, the cords from the drums of which are attached to the stabilizing planes and the elevating planes, respectively, the automatic controlling devices being at rest and inoperative. 100 105

What I claim, therefore, as my invention, is—

1. The combination with a flying machine provided with gyroscopic driving apparatus and with stabilizing devices normally free 110 from the driving apparatus, of automatic means whereby the gyroscopic action of said

driving apparatus causes corrective application of the force of the driving apparatus to the stabilizing devices when the machine tilts from its normal plane of movement.

5. 2. The combination with a flying machine provided with fore and aft and transverse stabilizing devices, of a gyroscopic propelling motor, for the machine, the stabilizing devices operable by said motor and normally disconnected therefrom, and means whereby the gyroscope upon tilting of the machine automatically produces corrective operation of the stabilizing devices by the motor.

10. 3. The combination with a flying machine having a gyroscopic driving motor, of fore and aft and lateral stabilizing devices operable by the motor and normally free therefrom, and means whereby the tilting of the machine in any direction causes the gyroscopic action of the motor to correctively connect the motor with the stabilizing devices and thus correct the tilting.

15. 4. The combination with a flying machine and its driving motor, of stabilizing devices operable by the motor and normally free therefrom, a power driven gyroscopic disk, means whereby the tilting of the machine causes said disk to connect the motor with the stabilizing devices correcting the tilting, and means for at will varying manually the point at which corrective action begins.

20. 5. The combination with a flying machine provided with a motor, fore-and-aft and transverse stabilizing devices, and a power driven gyroscopic disk, of devices carried by

the machine frame and adapted for contact with said disk at quadrantal points when the machine is correspondingly tilted, and means whereby such contact operates the corresponding stabilizing devices and corrects the tilting.

25. 6. The combination with a flying machine provided with a motor and fore and aft and transverse stabilizing devices, of a power-driven gyroscopic disk, rotary disks arranged at intervals around the gyroscopic disk in position to be actuated thereby when the machine tilts, and means whereby the rotation of any of said rotary disks actuates the stabilizing devices and corrects the tilting.

30. 7. The combination with a flying machine provided with a motor and fore-and-aft and transverse stabilizing devices, of a power driven gyroscopic disk, rotary disks arranged around the latter to be rotated by frictional contact therewith when the machine tilts, means whereby such contact actuates the stabilizing devices, and manually operable means for shifting all the rotary disks together, whereby the plane of the gyroscope and the plane of the machine may be varied, as in ascending and descending.

In testimony whereof I have affixed my signature in presence of two witnesses.

CHARLES FRANCIS JENKINS.
